UNITED STATES PATENT OFFICE

ISIDOR TORNBERG, OF PLAINFIELD, NEW JERSEY, ASSIGNOR TO WOOD NEWSPAPER MACHINERY CORPORATION, OF NEW YORK, N. Y., A CORPORATION OF NEW YORK

PNEUMATIC LADLE PUMP

Application filed February 2, 1926, Serial No. 85,570. Renewed January 10, 1930.

This invention relates to a stereotype metal pump for delivering molten metal to a plate casting machine.

The principal objects of the invention are to provide an efficient means for operating a pneumatic pump for constantly supplying molten metal to a ladle which will hold only a sufficient amount of metal by an intermittent operation of a valve to make a stereotype plate, and to mount the pouring spout of the pump in such a way, before casting, that it can be warmed up by circulating metal through it. Other objects and advantages of the invention will appear hereinafter.

Reference is to be had to the accompanying three sheets of drawings in which

Fig. 1 is a plan of a portion of a casting machine illustrating this invention;

Fig. 2 is a side view of the same partly in section showing the ladle in its upright position;

Fig. 3 is the same section through the ladle, but showing it in a pouring position; and

Figs. 4 and 5 are detail sectional views of the pump valve.

Instead of employing the customary gear pump continuously driven from a source of power such as an electric motor or the like, I employ the comparatively inexpensive and simple method of forcing metal from within the pot into the ladle pneumatically.

Referring to the drawings I have shown a receptacle 10 located within a melting pot 11 near one side and mostly below the level of the molten metal. It is suspended by means of brackets 13 which form a part of said receptacle. Extending up from said receptacle is a discharge tube 14. Centered and supported by the discharge tube 14 is a swinging spout 15 in which a ladle 16 is pivoted at 16^a. The ladle is provided with a counter balance weight 17 also a deflecting wall 18 which causes the incoming metal to go to the bottom and forces the metal already there to the top, where any surplus may be discharged back into the melting pot 11 through two side openings 19. Thus a constant level is maintained within the ladle

and a supply of fresh, hot molten metal is assured of uniform temperature throughout. The ladle is also provided with a cover plate 20 and a drain 21.

Pivoted at one side of the spout 15 is an arm 22 having a connection 23 provided with a handle 24. This handle extends out over the casting machine 25 so as to be easily accessible to the operator.

The receptacle 10 is provided with a chamber 26 and a valve 27 at the bottom. A valve seat 28 is provided and a limiting stop 29 for the valve 27. Air is admitted into the receptacle through the pipe 33 at regular intervals of time, so that the amount of metal forced out of the receptacle 10 into the ladle 16 may be replaced with metal from within the pot. This is accomplished by means of the valve 27, which, because of the difference of specific gravity, rises and opens the way for the passage of metal into the receptacle 10. As soon as pressure is applied by means of compressed air, the rush of metal closes the valve 27 so that no metal may escape from the receptacle 10 back into the melting pot 11, but instead the pressure forces whatever metal is trapped in the receptacle 10 up through the discharge tube 14 and nozzle 32 into the ladle 16. Any surplus metal will run back into the melting pot 11 through the drain openings 19.

The exterior surfaces 30 and 31 of the discharge tube 14 are finished so that the casting comprising a part of spout 15 can rotate on the same. Thus the discharge opening of the spout can be brought over the metal pot 11, so that it may be preheated by circulating metal through it into the melting pot, thus insuring that the first cast will not be chilled. The upper part of the discharge tube 14 is provided with opposite radial holes 40 so that metal may be delivered into a nozzle 32 in either of the two positions occupied by the spout 15.

Extending up from the top of the chamber 26 is a pipe 33 which is connected to a three-way air valve 34 for operating the pump. This valve is provided with an inlet pipe 35 and an outlet pipe 36.

Any means for continuously opening and

- closing the air valve 34 may be used but I have shown an eccentric 37 operated from a shaft 38. An eccentric strap 39 is attached to the handle 40 of the three-way valve 34. 5 Each revolution of shaft 38 opens and closes the valve 34 so that air is alternately admitted to and shut off from the receptacle 10. Thus the intermittent action of the air keeps the ladle constantly filled.
- 10 When it is desired to make a plate, it is merely necessary to pull the handle 24 attached to the connection 23 which tilts the ladle 16 on its pivots 16^a into the position shown in Fig. 3. This empties the entire 15 contents of the ladle 16 through the spout 15 into the casting machine 25. The counter balance 17 returns the empty ladle to its original position for refilling for its next 20 operation.
- 20 It will be seen that a very simple and efficient method of continuously raising the metal within the melting pot to the proper height for easy delivery into the casting box is provided, and only the desired amount of 25 metal can be held in the ladle.
- Although I have illustrated and described only one form of the invention, I am aware of the fact that modifications can be made therein by any person skilled in the art without departing from the scope of the invention as expressed in the claims.
- Therefore I do not wish to be limited to all the details of construction herein shown and described, but what I do claim is:—
- 30 1. In a pneumatic pump for molten metal, the combination with a melting pot and a receptacle located below the fluid metal level in the melting pot, said receptacle having a valve movable to admit metal to the receptacle from the pot, and having a discharge tube extending upwardly therefrom from below the liquid level of the receptacle, of automatic means for admitting air under pressure on the metal in the receptacle intermittently and regularly during the discharge of the metal.
- 35 2. In a pneumatic pump, the combination with a melting pot and a receptacle located in the melting pot, said receptacle having a valve movable to admit metal to the receptacle from the pot, and having a discharge tube extending from below the liquid level of the receptacle, of automatic means for admitting air under pressure on the metal in the receptacle intermittently, whereby the valve will be periodically closed and metal will alternately be forced out through the discharge tube and in past the valve a plurality of times during the flow of metal up the discharge tube.
- 40 3. In a pneumatic pump, the combination with a melting pot and a receptacle located in the melting pot, said receptacle having a valve movable to admit metal to the receptacle from the pot, and having a discharge

70 tube extending from below the liquid level of the receptacle, of automatic means for admitting air under pressure on the metal in the receptacle intermittently, said automatic means comprising an air pipe, a three-way valve for connecting the pipe with a source of air under pressure, a shaft, means operated by the shaft for alternately opening and closing the valve and means for continuously rotating the shaft during the casting operation.

75 4. In a pneumatic pump, the combination with a melting pot and a receptacle located in the melting pot, said receptacle having a valve movable to admit metal to the receptacle from the pot, and having a discharge tube extending from below the liquid level of the receptacle, of automatic means for admitting air under pressure, on the metal in the receptacle intermittently, and a pouring 80 spout rotatably mounted on said discharge tube so as to be movable to a position over the mold, for the purpose described.

85 5. In a pneumatic pump, the combination with a vertical discharge spout having a circular surface provided with openings therethrough communicating with the interior of the tube and means for keeping the metal constantly moving up the spout, of a pouring spout pivotally mounted on said tube and having a nozzle adapted to register with said 90 openings individually in different positions to deliver molten metal therethrough.

95 6. In a pneumatic pump for molten metal, the combination with a melting pot and a receptacle located below the fluid metal level in the melting pot, said receptacle having a discharge tube extending upwardly therefrom from below the liquid level of the receptacle, of automatic means for admitting air under pressure on the metal in the receptacle intermittently during the discharge of the metal, and a metal measuring device for receiving the metal and thereafter filling the mold.

100 In testimony whereof I have hereunto affixed my signature.

ISIDORE TORNBERG.
